(57) **CLAIM**

The ornamental design for a cigarette lighter holder as shown and described.

DESCRIPTION

FIG. 1 is a perspective view of the cigarette lighter holder showing my new design in an open configuration of use; FIG. 2 is another perspective view thereof; FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a perspective view of the cigarette lighter holder, shown in a closed configuration.

The broken lines in the drawings depict portions of the cigarette lighter holder that form no part of the claimed design.
